UNITED STATES PATENT OFFICE.

STRAUD K. WOOD, OF DENVER, COLORADO.

CERTIFICATE CONTAINER.

Application filed August 27, 1926. Serial No. 131,969.

This invention relates to a holder or casing for automobile license data, of such a character that once the sheet or card carrying this identifying information is placed within the container, it cannot be removed without mutilating the sheet or card, or destroying the container.

Such a container is particularly useful in States which permit a buyer of a used automobile using the old license tags upon registration of certain information. In such cases I propose to put this information upon the card to be held in the above container, and mounting said holder in a conspicuous place in the automobile, which is, in some States compulsory.

To this end the invention contemplates the provision of a two part complementary container adapted to hold the information sheet or card covered by a transparent glass or window, and a seal or strap passing through container, glass and card and fastened in such a manner that unauthorized breaking of the seal or strap will be apparent.

The invention further consists in the novel combination, construction and arrangement of parts hereinafter shown and described.

I have illustrated in the accompanying drawings one embodiment of my invention, in which:—

Fig. 1 is a front view of a device according to my invention.

Fig. 2 is a rear view of the device of Fig. 1.

Fig. 3 is a sectional view along the line 3—3 of Fig. 2.

Fig. 4 is a sectional view along the line 4—4 of Fig. 2.

Fig. 5 is a perspective view of the seal.

In these drawings I have shown at 1 a cover plate of substantially rectangular configuration and having a raised or pressed out portion 2 adapted to receive the information card or sheet 3 and a transparent member 4 such as glass or the like.

Around three sides of the cover plate, I provide flanges 5 having weakening indentations therein as at 6. These flanges are adapted to hug the back plate as will be hereinafter described.

In the raised portion 2 of the cover plate, is a window opening through which the information sheet may be viewed.

A back plate 7 having a flange 8 is adapted to be slid upon the cover plate so that

the flange 5 on the cover plate overlies the three unflanged edges of the back, and the flange 8 in the back plate overlies the unflanged edge of the cover.

The cover plate is cut away as at 9 and the back provided with offset ears 10 apertured as at 11 so that when these parts are assembled, the apertures register with the cut outs 9 and a stove or other bolt may be utilized to secure the assembly to some permanent part of an automobile.

The weakening indentations will cause the flanges to be broken off if one attempts to pry out these flanges to get at the information card in this manner, thus making unauthorized opening of the device apparent.

In order to secure the cover and back plates together and the glass and information sheet in the casing, so that they cannot be removed without mutilation, I provide a depression 12 in the back plate, forming a compartment in which I propose to place some sort of a locking device. This device may be of any desired character. The type of seal shown consists of the locking sphere 14 located in the offset portion of the plate. With the locking sphere 14, is used a strip or band 15 having one end fixed within the locking sphere 14, the other end having an aperture 17 and adapted to be retained within the sphere when inserted through one of the slots therein, all as is well known.

I propose to first place the lock sphere 14 in the offset portion of the casing, and then pass the band 15 through apertures in back plate, certificate, glass and cover plates across the front of the device and then down through registering apertures in cover, glass, certificate, and back. The free end of the band is then slipped through a slot 19 in the offset portion in the back plate and into the lock sphere where it is retained. As the strip is only long enough to pass through the various slots and into the lock 14, it leaves no room for play or manipulation in order to loosen the same.

By reason of this locking means, the parts are secured together in a manner that will not permit of separation without such tampering being apparent.

I propose to stamp the name of the State within which the device is to be used upon the outside of the cover plate as at 21. Likewise this State name may appear in sand blasted letters on the glass plate and also

printed on the certificate. In order to further prevent unauthorized use of the container, glass or certificate, I place the license number on the strap or band, and on the certificate. In this way no substitutions can be made without such substitution being evident.

Where the license number appears on the band 15, I may provide the casing plates 10 with an additional offset portion as at 22 which will contain another sphere seal 23. An extra strap 24 also bearing the license number, lies in recess 25. In this way when the car is sold, the plates may be separated 15 by cutting the strap, changing the certificate and then replacing the parts and locking the same with the spare strap which will bear the same license number.

Obviously the band or strap 15 may be 20 threaded through the container in the re-

verse manner as above described if this is found to be more convenient.

I claim:

1. In combination, front and back cover plates, a certificate and a glass held between said plates, an offset portion beneath said back plate, locking means located in said offset portion and between the back plate and the certificate and inaccessible from outside the device, and a metal element 25 threaded back and forth through plates, glass and certificate, the ends of said element being secured in said locking means.

2. The device of claim 1, with an additional offset portion in said back plate 30 adapted to receive a reserve locking means and metal element.

In testimony whereof, I affix my signature.

STRAUD K. WOOD.
